SIGNORS TO THE BARTLETT-COLLINS GLASS COMPANY, OF SAPULPA, OKLAHOMA,
A CORPORATION OF OKLAHOMA.

METHOD AND APPARATUS FOR RE-FORMING GLASS ARTICLES.

Application filed July 7, 1924. Serial No. 724,580.

To all whom it may concern:

Be it known that we, HARRY A. BRIDGES, a citizen of the United States, residing at Sapulpa, county of Creek, and State of Oklahoma, and JOHN WM. LAMPARTER, a citizen of the United States, residing at Sapulpa, county of Creek, and State of Oklahoma, have invented a new and useful Improvement in Methods and Apparatus for Re-forming Glass Articles, of which the following is a full, clear, and exact description.

The present invention relates broadly to the re-shaping or re-forming of glass articles, such as tumblers and the like, during their manufacture.

An object of the invention is to provide an apparatus for this purpose whereby the cost of production of such articles may be reduced while maintaining their quality and durability comparable with articles re-formed by the former hand finished method.

Other objects and advantages of the invention will be apparent as the description proceeds.

In the accompanying drawings, there are shown, for purposes of illustration only, certain embodiments of our invention, it being understood that the drawings do not define the limits of the invention, as changes may be made in the construction and operation therein disclosed without departing from the spirit of the invention or scope of our broader claims.

In the drawings:

Figure 1 is a view partly in elevation and partly in vertical section illustrating one embodiment of our invention;

Figure 2 is a top plan view illustrating the re-forming cup and the means for supplying a cooling medium thereto;

Figure 3 is a vertical sectional view of a modified form of re-forming member;

Figure 4 is a vertical sectional view illustrating another modified form of re-forming member; and

Figure 5 is a top plan view of the re-forming structure shown in Figure 4.

As illustrated in the drawings, our apparatus comprises a table 2 which may be supported in any suitable manner in an elevated position relative to the floor. Preferably the table 2 will be mounted upon a

wheeled support (not shown) in order to render the apparatus portable.

Referring to the construction shown in Figure 1, fastened to the under side of the table by means of bolts 3 is a hanger or bracket 4 provided with spaced bearings 5 for a vertical hollow shaft 6. The shaft 6 has the hub 7 of a chuck 8 mounted upon the upper end thereof, the hub extending through an opening 9 in the table 2 and the chuck being positioned in a horizontal plane slightly above the upper face of the table. Interposed between the lower end of the hub 7 and the upper side of the upper bearing 5 is a thrust bearing 10 and mounted upon the shaft 6 and engaging the upper side of the lower bearing 5 is a worm gear 11. The worm gear 11 is in engagement with a worm 12 driven from any suitable source of power, such as a motor (not shown), suspended from the under side of the table 2.

The rotatable chuck 8 is provided with means whereby a suitable re-forming member such as the cup 13 shown in Figure 1 or the member 14 shown in Figure 3, may be quickly attached thereto or detached therefrom. For this purpose, the chuck has a plurality of headed pins 15 projecting at intervals above its upper marginal surface. These headed pins are adapted to cooperate with key-hole slots 16 in an outwardly extending flange 17 formed on the lower end of the re-forming member. The re-forming member is provided with a circular extension 18 projecting below the base flange 17 and fitting in a circular recess 19 in the chuck to thereby center the re-forming member with respect to the chuck. The chuck is also provided with a locking pin 20 working in a recess in said chuck, the head of said pin being normally maintained above the upper surface of the chuck by a spring 21.

In attaching the re-forming member to the chuck, said member is applied thereto so that the heads of the pins 15 will pass through the enlarged portions of the slots 16 and the member is pressed downwardly to seat it upon the chuck and to depress the pin 20 against the action of the spring 21. The member is then rotated to position the pins 15 in the narrow portions of the slots 16 and to allow the head of the locking pin

20 to snap into the recess 22 in the member. In this position of the parts, the heads of the pins 15 engage the upper surface of the flange 17 and hold the re-forming member 13 on the chuck. When it is desired to remove the re-forming member, it is only necessary to first depress the pin 20 by means of a suitable tool inserted in the opening 22 until the head of said pin is flush with or below 10 the upper surface of the chuck and then to rotate the re-forming member until the pins 15 are in the enlarged portions of the slots 16, whereupon the re-forming member may be removed from the chuck.

15. Rising vertically from the table 2 adjacent the chuck 8, is a standard 23 having its lower end 24 reduced and extending through an opening in said table. The upper portion 25 of the standard is reduced, 20 thereby forming a shoulder 26 at the junction of the reduced portion with the lower portion of said standard. An arm 27 is mounted upon the reduced portion 25 by means of a collar 28 at one end of said arm 25 surrounding said reduced portion and resting upon said shoulder 26. The arm 27 is adapted to be angularly adjusted with respect to the standard 23 and secured in adjusted position by means of a set-screw 29 30 carried by said collar 28 for engagement with said reduced portion 25.

A lever 30 is provided at one end with a sleeve 31 by means of which said lever is journaled upon the reduced portion 25 of said standard, the said sleeve engaging the upper end of the collar 28. The lever 30 has secured thereto by means of a bolt 32 a clamp 33 holding a pipe 34. The pipe 34 carries at its lower end a suitable nozzle 35 and has secured to its upper end a valve casing 36 through which extends the stem 37 of a spring-pressed valve (not shown).

40 Referring to Figure 2, it will be seen that the arm 27 carries a screw 38 forming an adjustable stop and that a coil spring 39 fastened at one end to the arm and at the other end to the lever 30, normally maintains said lever against the stop.

45 A pair of spaced clamp brackets is carried by the reduced portion 25 of the standard 23 above the lever 30, each clamp bracket having a split collar surrounding said reduced portion and clamped thereto by means of a bolt 41. Each bracket 40 is provided in 50 its upper surface with a channel 42 to receive a guide plate 43, which is adjustably secured in said channel by means of a bolt 44 extending through a slot 45 in the plate. The outer extremity of each plate 43 is 55 forked to receive the guiding stem 46 of a punty 47.

60 By reference to Figures 1 and 2, it will be apparent that the valve stem 37 is in the plane of the lower clamp bracket 40. In 65 this position of the parts the valve is closed

and in order to move the nozzle 35 in position to supply a cooling medium to the re-forming member on the chuck 8 and to open the valve, it is necessary to rotate the lever 30 away from the stop screw 38 until the valve stem 37 engages and is pushed inwardly by the edge of the bracket. The valve casing 36 is connected by suitable means (not shown) with a source of fluid supply constituting a cooling medium, so that when the valve is unseated the cooling medium will flow through the nozzle 35 upon the shaping surface of the re-forming member. In order that the valve stem may abut squarely against the edge of the lower bracket 40, a notch is formed in said edge to provide the inclined surface 48.

70 As shown in Figure 1, the re-forming member 13 is generally cup shaped. The internal surface of this cup-like member is 75 formed of material which will not in any way mar or injure the glazed surface of the glass article, such as the tumbler 49, carried by the punty 47. The shape of the internal surface of the member 13 is such that a vertical plane containing the axis of the member intersects said surface in lines having a compound curvature, said internal surface flaring outwardly at the upper end of said member.

80 Furthermore, the internal shape of the member 13 is such that the portion of each horizontal plane passing therethrough and bounded by said internal surface is a polygon instead of a circle. This will be apparent by reference to Figure 2 wherein the member 13 is shown as having a hexagonal shape in its interior, it being understood, 90 however, that the number of sides may be varied as desired.

95 The operation of the apparatus described is substantially as follows: The glass article to be re-formed, such as the tumbler 49 shown in Figure 1, is fastened to the punty 47 by sticking said punty to said article. The article is then reheated to glaze and soften the same. The stem 46 of the punty is then passed between the guiding forks of the plates 43 and the punty lowered to enter the 100 end of the article 49 into the revolving cup 13. As the re-shaping or re-forming progresses, the punty is gradually lowered until a stop collar 50 adjustably secured to the stem 46 by means of a set-screw 51 engages the lower guide plate 43. The adjustable stop regulates the depth to which the article 49 enters the cup member 13. When the article has become set in the new shape indicated in dotted lines in Figure 1, the punty is raised to remove the article from the re-forming member 13 and the article is 110 then removed from the punty.

115 The purpose of giving the internal surface of the re-forming member a polygonal instead of a circular shape, as above ex-

plained, is to cause a series of waves in the walls of the glass article while hot and plastic, the diameter of portions of the article being gradually reduced and the walls thereof becoming thicker as this difference in diameter takes place. The gradual reduction in diameter and working of the glass by means of a polygonal surface eliminates the danger of buckling the glass, such as would occur if it were attempted to simultaneously reduce the entire perimeter of the glass body.

During the re-forming operation it is necessary to regulate the temperature of the shaping surface of the re-forming member. This is accomplished by means of the cooling medium supplied through the nozzle 35 when the controlling valve is unseated by rotating the lever 30 away from the stop 38 to bring the valve stem 37 into engagement with the edge of the lower clamp bracket 40 and position the nozzle 35 over the upper end of the re-forming member, as already explained. The cooling medium may be applied to the re-forming member at desired intervals and when said member is sufficiently cooled the lever 30 may be released and the spring 39 will immediately draw said lever against the stop 38 and the controlling valve will automatically close. The cooling medium will preferably be a liquid and in the construction shown in Figure 1, where a cup-like re-forming member is employed, the waste liquid may be drained away through the hollow shaft 6.

In case it is desired in re-forming the articles to give them an outward flare instead of a reduced diameter at their open ends, a re-forming member in the form of the frustum of a pyramid may be employed instead of the cup-like member 13. This modified form of re-shaping member is illustrated in Figure 3.

In Figures 4 and 5 a re-forming member 52 is shown similar in shape to the re-forming member 14 illustrated in Figure 3, but made in a plurality of parts, whereby such parts may be moved relatively to each other in the re-forming operation for the purpose of varying the shape of the article being re-formed. The member 52 is carried by a chuck 8', the hub 7' of which is keyed to the upper end of a shaft 6'. Interposed between the hub 7' and a bearing 5' is a thrust bearing 10'. The chuck 8' is provided in its upper surface with a plurality of radially extending grooves 53 having undercut edges. The sections of the re-forming member 52 are slidably mounted at their lower ends in these radial grooves and each section of the member has a stem 54 extending downwardly through a radial slot 55 in the chuck and through a cam slot 56 in a plate 57 journaled upon the hub 7' and engaging the lower face of the chuck. The lower end portion of each

stem 54 is screw-threaded and has mounted thereon, a thumb-nut 58 for holding the sections of the re-forming member in the grooves 53 and the plate 57 on the hub 7'. The plate 57 is provided with outwardly extending lugs 59 by means of which it may be rotated. By loosening the thumb-nuts 58 and rotating the plate 57, the sections of the re-forming member 52 may be moved outwardly or inwardly to the desired position because of the engagement of the stems 54 in the cam slots 56. When the sections of the re-forming member have been moved to the desired position, they may be clamped in such position by tightening the nuts 58.

While we have described our method as being carried out by revolving the re-forming member relatively to the article being shaped, it will be understood that the re-forming member may be held stationary and the article rotated, and it will also be understood that the re-forming member may be moved toward and from the article being re-formed instead of the article being moved toward and from the re-forming member. Moreover the re-forming member might be rotated in one direction and the article being re-formed rotated in the reverse direction. In our broader claims we desire and intend to cover these alternative methods of operation, in which there is a relative movement between the glass and re-former, irrespective of how such relative movement is obtained.

The advantages of the present invention arise from the provision of an apparatus of simple construction whereby the re-shaping or re-forming of glass articles may be accomplished in a more expeditious manner than by the usual hand method and at a reduced cost of production without lowering the quality and durability of the articles and without danger of buckling.

We claim:

1. In a method of re-forming articles of glassware, the steps consisting in heating the article to be re-formed to soften the same, engaging said article with a shaping surface, producing relative rotation between said article and surface, and supplying a cooling medium to said shaping surface, substantially as described.

2. In apparatus for re-forming articles of glassware, a re-forming member, means for holding an article to be re-formed in operative relation to said member, means for producing relative rotation between said holding means and member, and means for supplying a cooling medium to said member, substantially as described.

3. In apparatus for re-forming articles of glassware, a chuck, means for rotating said chuck, a re-forming member mounted on said chuck, means for detachably securing said re-forming member to said chuck effective to release said member from said chuck

upon relative rotation between said member and chuck, guiding means adjacent said chuck, and means engageable with said guiding means for holding an article to be re-formed in operative relation to said re-forming member, substantially as described.

4. In apparatus for re-forming articles of glassware, a chuck, means for rotating said chuck, a re-forming member detachably mounted on said chuck, guiding means adjacent said chuck, means engageable with said guiding means for holding an article to be re-formed in operative relation to said re-forming member, and means mounted on said standard for supplying a cooling medium to said re-forming member, substantially as described.

5. In apparatus for re-forming articles of glassware, a re-forming member, means for supporting and rotating said member, a standard adjacent said member, a stop on said standard, a lever journaled on said standard, a spring normally maintaining said lever in engagement with said stop, and means for supplying a cooling medium to said re-forming member, comprising a pipe carried by said lever, a nozzle connected to said pipe and adapted to be brought into operative relation to said member by movement of said lever away from said stop, a valve carried by said pipe, and an abutment

carried by said standard and adapted to engage and unseat said valve upon movement of said nozzle into operative relation with respect to said re-forming member, substantially as described.

6. In apparatus for re-forming articles of glassware, a supporting table having an opening therein, a vertical hollow shaft journaled in bearings arranged below said table, a chuck positioned in a horizontal plane above said table and having a hub secured to the upper end of said shaft, said chuck having a recess communicating with the bore of said shaft, and a cup-like re-forming member detachably secured to said chuck and opening at its bottom into said recess, whereby a cooling medium supplied to said re-forming member is permitted to drain through said hollow shaft, substantially as described.

7. In apparatus for re-forming articles of glassware, a re-forming member formed in a plurality of sections adapted for movement toward and from each other and provided with a shaping surface having a polygonal form in cross-section, substantially as described.

In testimony whereof we have hereunto set our hands.

HARRY A. BRIDGES.
JOHN WM. LAMPARTER.
